UNITED STATES PATENT OFFICE.

GEORGE LEACHMAN, OF NEW CUMBERLAND, WEST VIRGINIA.

PORTABLE DARK CABINET.

1,159,966.

Specification of Letters Patent.

Patented Nov. 9, 1915.

Application filed September 8, 1914. Serial No. 859,992.

To all whom it may concern:

Be it known that I, GEORGE LEACHMAN, a citizen of the United States, and a resident of New Cumberland, in the county of Hancock and State of West Virginia, have invented a new and Improved Portable Dark Cabinet, of which the following is a full, clear, and exact description.

My invention has for its object to provide a portable dark cabinet having a table with a frame disposed above the table which is connected with the table by a hood, the rear of the frame being hinged to its forward portion so that the rear of the frame with the rear of the hood may be raised to permit the operator to place on the table the materials desired, and to enter the hood through an opening in the bottom thereof at the rear of the table.

Additional objects of the invention will appear in the following specification, in which the preferred form of my invention is described.

In the drawings similar characters of reference indicate corresponding parts in all the views, in which—

Figure 1 is a front elevation showing my invention; Fig. 2 is a side elevation of Fig. 1; Fig. 3 is a sectional view on the line 3—3 of Fig. 2; Fig. 4 is an enlarged fragmentary sectional view showing the means for supporting the table on the standards; Fig. 5 is a perspective view showing the means for securing the hood around the waist of the operator; and Fig. 6 is a perspective view showing the frame.

By reference to the drawings, it will be seen that two standards 10 are provided, these standards 10 having adjustable collars 11 which may be held in adjusted position by means of clamps 12, a table 13 being provided and having at its sides resilient clamps 14 for embracing the standards 10 above the collars 11 so that the collars 11 will support the table by means of the clamps 14. The table 13 may be readily raised when desired and it may be held in any position desired by means of the collars 11 which may be secured to the standards in the manner described. The resilient clamps 14 are disposed at the rear of the sides of the table 13, it being possible to move the table 13 rearwardly to readily disengage the table from the standards. A hood 15 is secured to the

sides and the front and the rear of the table 13, this hood 15 being supported above the table by means of the frame 16, the frame 16 having a bracket 17 with an opening 18 through which the top of the standards 10 are disposed, the standards also being disposed through the orifices 19 in the flanges 20, each secured to the sides of the forward portion of the frame 16. The standards 10 have shoulders 21 which engage the flanges 20 at the sides of the orifices 19.

As has been stated, the hood 15 is disposed over the horizontal frame 16, the forward portion of which is supported by the standards 10 in the manner described. The rear portion 22 of the frame 16 is hinged at 23 to the forward portion of the frame 16 so that the rear portion 22 of the frame may be raised with the rear portion of the hood to permit the operator to place materials on the table 13 through the opening 24 in the bottom of the hood 15 at the rear of the table 13. When the desired materials have been placed on the table 13 through the opening 24, the operator then inserts the upper portion of his body through the said openings, this being easily accomplished since the hood 15 will be supported by the portion 22 of the frame 16 which has been raised as set forth. When the operator has inserted the upper portion of his body through the opening 24 the straps 25 secured to the hood 15 at the opening 24 are drawn together and are secured by means of the fastening members 26. It will be noted that the clamps 14 are to be constructed of sufficient strength to hold the table 13 in adjusted position after it has been raised or lowered and without any support from the collars 11. In this way the operator may adjust the table while operating within the opening 24 in the hood 15.

At one side of the hood 15 there is, preferably, an opening 27 with a tube 28 secured to the hood 15 at the sides of the opening, the tube 28 having a mask 29 which may be secured over the face of the operator to permit the operator to breathe fresh air while working within the hood.

The table 13 has a leaf 13^a which is hinged at 13^b to the table. This leaf 13^a may be folded against the table when the cabinet is not in use.

The ruby glass window 27 is hinged at

27^a in a frame 30 secured in an opening 31 in the hood 15.

Having thus described my invention, I claim as new and desire to secure by Letters 5 Patent:

1. In a portable dark cabinet, a table, a horizontal frame having its rear hinged on a horizontal axis to its forward portion, the forward portion of the horizontal frame being disposed above the table, a hood secured 10 around the frame, means for supporting the frame, the hood being secured to the front and to the sides of the table and extending down from the frame at the rear of the 15 table, the hood having a bottom portion secured at the rear of the table, and extending horizontally from the table, the said bottom of the hood being provided with an opening, for the purpose specified.
2. In a portable dark cabinet, two standards, a table, resilient clamps on the table for embracing the standards, a horizontal frame having its forward portion secured to the standards and its rear portion hinged 25 to its forward portion and extending rearwardly of the vertical plane at the rear of the table, and a hood secured around the frame, the hood being secured to the front and to the sides of the table and extending 30 down from the frame at the rear of the table, the hood having a bottom portion, secured at the rear of the table, and extending horizontally from the table, the said bottom

of the hood being provided with an opening, for the purpose specified.

3. In a portable dark cabinet, a table, a horizontal frame having its rear hinged to its forward portion, means for supporting the frame above the table, a hood connecting the frame with the table and having an entrance opening in the rear of the table, there being an orifice in the hood, and an air tube secured at one end to the hood around the orifice therein and having at the other end 40 a mask fitting the face of the operator.

4. In a portable dark cabinet, a table, two standards extending upwardly from the sides of the table, a horizontal frame having its forward portion disposed above the table and supported by the standards, the rear of the horizontal frame extending rearwardly of the vertical plane at the rear of the table, a hood having an entrance opening connecting the frame with the table, there being an orifice in the hood, and an air tube secured at one end to the hood around the orifice and provided with a mask at the other end for fitting the face of the operator.

In testimony whereof I have signed my name to this specification in the presence of 30 the subscribing witnesses.

GEORGE LEACHMAN.
